UNITED STATES PATENT OFFICE.

EDWARD E. PORTER, OF CINCINNATI, OHIO, ASSIGNOR TO THE UNION PAPER BAG MACHINE COMPANY, OF PHILADELPHIA, PENNSYLVANIA.

PRESS FOR BUNDLING.

SPECIFICATION forming part of Letters Patent No. 440,194, dated November 11, 1890.

Application filed March 1, 1890. Serial No. 342,280. (No model.)

To all whom it may concern:

Be it known that I, EDWARD E. PORTER, of Cincinnati, county of Hamilton, State of Ohio, have invented a certain new and useful Improved Press, of which the following is a true and exact description, reference being had to the accompanying drawings, which form a part of this specification.

My invention relates to presses especially designed and adapted for use in compressing bundles or packages, such as packages of paper bags.

The object of my invention is to construct a simple and powerful press which can be readily adjusted for use with packages of different thicknesses.

The nature of my invention will be best understood as described in connection with the drawings, and the novel features which I desire to protect by this patent are herein-after clearly set forth in the claims.

In the drawings, Figure 1 is a plan view of my improved press, showing the package in place between the presser-plates thereof. Fig. 2 is a central longitudinal elevation on the section-line $x-x$ of Fig. 1. Fig. 3 is a cross-sectional elevation on the line $y-y$ of Fig. 1, and Fig. 4 is a cross-sectional elevation on the line $z-z$ of Fig. 2.

A is what may be called the "base-plate," on which the press is supported. A central groove a is formed in it to receive the pins of the removable bundle-plate, hereinafter described, and a larger central groove a^3 is formed in its opposite end to receive the adjusting-screw D and the lug c of the stay-plate C .

A' is a plate bolted to the end of the base-plate A across the slot a^3 , and A^2 an upwardly-projecting plate on the opposite end, which serves the purpose of a clamping-plate. Grooves $a' a'$ (see Fig. 4) are formed in the sides of the plate A .

B are bearings or plates acting as bearings. They are bolted by bolts b' to sliding plates B' , which are provided with projections b , fitting in the grooves a' of the base-plate, and also with projections b^4 , serving a purpose hereinafter described.

To the top of the bearing-plates B are bolted stay-arms B^2 , which stay-arms are also bolted to a

sliding back-stay C , adjusted to slide on the top of the base-plate A and provided with a downwardly-extending internally-threaded lug c , which projects into the grooves a^3 of the base-plate. The sliding plates B' are also bolted to the back-stay C , as by the bolts b^5 , &c., so that the back-stay and the bearings B are rigidly and securely fastened together.

D is a screw fitting into the threaded perforation c of the back-stay and passing through a perforation a^4 in the plate A' , on each side of which it is provided with collars d' and d^2 to prevent longitudinal movement, and with a hand-wheel d , by which the screw can be turned.

F is a shaft journaled in the bearing-plates B and having secured upon it a wrist-supporting device G , from which project the wrist-pins $g g' g'$.

H are links pivoted to the back-stays C and to the wrist-pins $g g'$.

E is a movable presser-plate and its supports. As shown, the backwardly-extending arms of the plate-support are provided with grooves $e e'$, fitting onto the projections b^4 of plate B' .

I are links pivoted to pins $e' e'$ on the movable presser-plate and to the wrist-pins $g' g'$.

M is a lever by which the wrist-supporting device G is turned.

J is a bundle-supporting plate, which is made so as to be readily removable from the press. It is provided with downwardly-projecting pins j' , which fit in the groove a of the base-plate. The breadth of this plate is that of the bundle which is to be compressed between the presser-plates of the press, and at each end it is provided with abrupt corners $j' j'$.

K indicates a package of paper bags upon which the press is operating, and L self-locking presses between which the ends of the bundle are clamped, and which hold the bundle in the state of compression given to it by the press. These self-locking presses L are made in accordance with the invention described in my patent granted April 16, 1889, and numbered 401,587, embodying also certain improvements on the said patented self-locking press for which I am about to file another application for Letters Patent. The clamping-plates of the self-locking presses L

- are provided with lateral extensions $l\ l$, which extend below the sharp corners $j' j'$ of the bundle-supporting plate J and prevent the self-locking presses from being shoved up
- 5 5 against the ends of the bundle K, thus insuring that the bundle is in proper position, and when it is compressed that the self-locking presses holding its ends shall not interfere with the operation of wrapping it.
- 10 10 By turning the hand-wheel d and the screw D, the back-stay C, bearing-plates B B, and all the movable parts of the press proper are adjusted in a longitudinal direction, and thus adapted for use on packages of different thicknesses. The operation of pressing a bundle is performed simply by drawing down the lever M and turning the wrist-pin support G. The links H H and I I act as a toggle-joint, pressing the movable presser-plate E forward
- 15 15 with any desired degree of power.
- Having now described my invention, what I claim as new, and desire to secure by Letters Patent, is—
- 20 20 1. In a press, the combination of the longitudinally-adjustable bearings B B and longitudinally-adjustable back-stay C, firmly attached to said bearings, mechanism for adjusting said parts, a shaft F, journaled in the bearings B B, a wrist-support G, attached to
- 25 25 said shaft, wrist-pins $g\ g'\ g'$, attached thereto, links H, pivoted to the back-stay C and wrist-pins g , a sliding presser-plate E, links I I, pivoted to said plate and to the wrist-pins g' , and a stationary coacting presser-plate A²,
- 30 30 35 all substantially as and for the purpose specified.
2. In a press, the combination, with the sta-

ticary presser-plate A² and movable presser-plate E, of a removable package-holding plate J, with abrupt corners $j' j'$, arranged beneath 40 the plate E.

3. In a press, the combination of the longitudinally-adjustable bearings B B and longitudinally-adjustable back-stay C, firmly attached to said bearings, mechanism for adjusting said parts, a shaft F, journaled in the bearings B B, a wrist-support G, attached to said shaft, wrist-pins $g\ g'\ g'$, attached thereto, links H, pivoted to the back-stay C and wrist-pins g , a sliding presser-plate E, 50 links I I, pivoted to said plate and to the wrist-pins g' , a removable package-holding plate J, having abrupt corners $j' j'$, and a stationary coacting presser-plate A², all substantially as and for the purpose specified. 55

4. In a press, a frame A, having grooves $a' a'$, sliding plates B' B', having projections b engaged in grooves a' , and projections $b^4 b^4$ on their upper edges, journal-bearings B B, secured to plates B' B', a longitudinally-adjustable stay C, firmly secured to the bearings B, mechanism for adjusting said stay and its connected bearings B, a movable presser-plate and support E, having grooves e , engaged with projections b^4 , a shaft F, journaled in bearings 60 B B, a wrist-support G, attached to said shaft, wrist-pins $g\ g'\ g'$, attached to said wrist-support, links H H, pivoted to stay C and to wrist-pins g , links I I, pivoted to plate E and pins g' , and a stationary presser-plate A². 65

EDWARD E. PORTER.
